UNITED STATES PATENT OFFICE.

EDWARD J. F. REA, OF HARTFORD, CONNECTICUT, ASSIGNOR TO AMERICAN AUTOMATIC PRESS COMPANY, OF SAN FRANCISCO, CALIFORNIA, A CORPORATION OF CALIFORNIA.

INK-DISTRIBUTING MECHANISM.

1,074,066.

Specification of Letters Patent. Patented Sept. 23, 1913.

Application filed September 19, 1912. Serial No. 721,224.

To all whom it may concern:

Be it known that I, EDWARD J. F. REA, a citizen of the United States, residing at Hartford, in the county of Hartford and State of Connecticut, have invented certain new and useful Improvements in Ink-Distributing Mechanism, of which the following is a specification.

This invention relates to ink-distributing mechanism for printing presses, the principal object of the invention being to provide effective means of this character by which the ink can be uniformly distributed.

The apparatus comprises other features of novelty and advantage which with the foregoing will be set forth at length in the following description wherein I will outline in detail two of the several forms of embodiment of the invention which I have selected for illustration in the drawings accompanying and forming part of the present specification, this disclosure being provided to enable those skilled in the art to practice the invention. From such observation it will be evident that I do not restrict myself to said disclosure; I may depart therefrom in several respects within the scope of the invention defined by the claims following said description.

Referring to said drawings: Figure 1 is a side elevation with parts removed, of a printing-press equipped with ink-distributing mechanism involving my invention.

Fig. 2 is a sectional side elevation of the rollers with certain of their operating parts. Fig. 3 is an elevation of the parts shown in Fig. 2 as seen from the right thereof, with the central portions of said rollers removed. Fig. 4 is a somewhat similar view with certain of the operating elements removed, and only the ends of the rollers being shown.

Fig. 5 is a top plan view of the parts shown in Fig. 4. Fig. 6 is an inside face view of a supporting box, which sustains the rollers at one end. Fig. 7 is a perspective view of the boxes assembled and which support the other end of said rollers. Figs. 8 and 9 are like views of the boxes shown together in Fig. 7 separated from each other. Fig. 10 is a top plan view of a different form of roller mechanism, and Fig. 11 is a sectional view of the same.

Like characters refer to like parts throughout the several views which it will be perceived are on different scales.

At the outset I wish to make it clear that my improvements can be used with advantage in various connections; for instance the same may be incorporated in a printing or a lithographing press. In Fig. 1 of the drawings I have illustrated for convenience in indicating the utility of the improved organization, a press of known construction, certain of the well known parts of which will be briefly described, and which embodies mechanism including the invention. Said press has its different operative parts sustained by framework, such as that denoted in a general way by 2. The power-shaft 3 is carried by suitable bearings on the sides of the framework, and may be driven in any desirable manner, for example by the pulley or belt-wheel 4. In the construction shown, the moving parts of the ink-distributing mechanism, receive their motion from said power-shaft 3 although in all cases this is not necessary. I will hereinafter describe the connections between said shaft 3 and said ink-distributing mechanism, but I do not limit myself thereto. The press is shown equipped with a reciprocatory ink-table 5 which receives ink at one end thereof from the font 6. Jointed to the underside of the ink-table 5, is the pitman or connecting rod 7 pivoted to a crank-arm 8 on the shaft 9 provided with a spur gear 10 in mesh with the pinion 11 of the main shaft 3. It will therefore be understood that as said power-shaft rotates, the table 5, through the intermediate described parts will be caused to reciprocate all as common in the art.

There are preferably at least two ink-distributing rollers one arranged above the other, the lower roller being rotated by frictional contact with the bed 5 while said lower roller in turn frictionally drives the upper coöperating roller in the opposite direction. In the construction shown there are three of said lower rollers and three of said upper rollers. The lower rollers are denoted by 12, 13, and 14 while the upper rollers are designated by 15, 16 and 17 respectively. It will be evident that the three lower rollers are rotated by direct contact with the reciprocatory bed while the upper rollers are turned by contact with the respective lower rollers. Each upper roller is reciprocated oppositely to a coöperating lower roller, as will hereinafter appear, to thereby better distribute the ink and power-operable means

preferably including a rack and oscillatory or rocking pinion, is provided for this purpose, said means being positive and certain in action and as already intimated being 5 preferably operable from the main or power shaft 3, as will hereinafter appear.

All the rollers are confined against lateral movement at one end by a box or standard such as that denoted by 18 (Fig. 6,) 10 which is rigidly mounted on the frame work of the press, said box as shown having channels 19 to receive the outer end journals 20 of said rollers. Three of such rollers 12, 14 and 16 reciprocate together as a set, the 15 other three rollers 13, 15 and 17 reciprocating also as a set and oppositely to the other set by virtue of which each roller is always when in endwise action, moving oppositely to the contacting roller. In mounting 20 the several rollers, the journals 20 are dropped into the channels 19 through the upper open ends thereof.

There are two boxes or bearings which support the other journals of said six rollers 25 and one of them fits slidably within the other both being slidable or reciprocative transversely of the machine, the framing of which has suitable bearings therefor. One of said slidable boxes is denoted by 25 and 30 the other by 26, the box or bearing 25 fitting within the box 26 as shown best in Fig. 7. The box 25 comprises in its make up a substantially yoke-like body 27 provided with lateral extensions 28 on the upper ends of 35 its side branches, said extensions and the transverse portion of said body 27 having slots 29, T shaped in cross section, to rotatably receive the correspondingly-shaped adjacent journals of the rollers 13, 15 and 40 17. The block or bearing 26 is of substantially inverted yoke form and from the ends of the sides thereof there are extended inward the square projections 30 and 31, the cross bar thereof having a depending similar 45 projection 32, said several projections 30, 31 and 32 having T slots 33 to receive the T shaped adjacent journals of the rollers 13, 14 and 16. It will therefore be apparent that each of said blocks or boxes 25 and 26 50 acts to reciprocate three of the ink-distributing rollers. The heads or transverse portions of the journals supported by the blocks or boxes 25 and 26 are of disk or circular form so as to insure the reciprocation of 55 said rollers but not to effect the free rotation thereof. The block 25 is provided with an outwardly-extending rack-bar 34, while the block 26 is equipped with a practically similar rack-bar 35, the teeth of the two rack-bars being in mesh with the intermediate 60 pinion 36, it being understood that the two groups of rack-bar teeth face inwardly or toward each other. As will hereinafter appear this pinion 36 is rocked and as it is 65 thus operated the two sets of ink-distribut-

ing rollers through the invention of the described parts, are reciprocated in the manner already set forth. The framework of the machine is furnished with a guide as 37 for the rack-bar 38 which has two sets of 70 teeth, one set of teeth being in mesh with the pinion 36 and the other set being in mesh with the pinion 39 fastened to the shaft 40. Said shaft 40 also rigidly carries the pinion 41 the teeth of which are 75 in mesh with teeth on the reciprocatory rack bar 42 upheld by a stirrup 43 suspended flexibly from the shaft 40. The rack-bar 42 terminates in a strap 44 surrounding the eccentric 45 on the shaft 9 which I have 80 already described. It will therefore be evident that when the press is in action, the ink-table 5 is reciprocated, thereby rotating directly the lower set of ink-distributing rollers while at the same time said lower 85 rollers by contact, rotate oppositely the respective upper rollers. At the same time, three of said rollers are being reciprocated in unison with each other while three other of said rollers are being simultaneously reciprocated in unison with each other but oppositely to the other rollers all as practically described hereinbefore.

In Figs. 10 and 11 I show a different mounting of ink-distributing rollers, there being as in the other cases three lower rollers and three upper rollers denoted by 50. Each roller has at one end a journal 51 having a T head 52, said T heads fitting for rotation T slots 53 in the bearing blocks 54, there being three lower bearing blocks and three upper bearing blocks, the upper bearing blocks being supported for sliding movement by the lower bearing blocks 100 slidable within the skeleton and substantially rectangular frame or carrier 55 mounted on the main frame of the machine. Said blocks being slidable in the direction of the axes of rotation of said rollers 50. Tapped into the outer faces of said bearing blocks are racks 56, the three upper racks facing the three lower racks. Supported by suitable bearings on the frame-work of the press, is the shaft 57 to which are fastened the pinions 58 and 59, which mesh with the 110 teeth of the two pairs of outer racks, the two intermediate racks being in mesh with the pinion 60 fastened to the shaft 61 also supported by suitable bearings on the frame-work of the machine. Fastened to the shaft 115 61 is the second pinion 62 in mesh with the wide faced or barrel pinion 59. Connected with the shaft 61 is the rock-arm 63 which is oscillated exactly as already described and which when operated rocks the shaft 61, 120 and consequently the two pinions 60 and 62 thereon, the pinion in turn rocking the barrel pinion 59 oppositely and hence the shaft 57 and pinion 58 oppositely, so that the six racks will be reciprocated oppo- 130

sitely in sets of three, the two outside lower rollers and the upper middle roller moving together and the two outside upper rollers and the middle roller moving together and the two outside upper rollers and the middle lower roller moving together in the construction shown. This is exactly as the other rollers are operated although it is not an essential though an advantageous movement.

10 What I claim is:

1. The combination of an ink table, ink distributing rollers, slideable bearing blocks disposed in superposed order, the upper bearing blocks being supported by the lower bearing blocks, said rollers being rotatively supported by the respective bearing blocks, and means for reciprocating said bearing blocks in the direction of the longitudinal axes of the rollers and in opposite directions to each other.

2. The combination of an ink-table, ink-distributing rollers, rack bars connected with the respective rollers, and oppositely-oscillatory pinions in mesh with sets of the rack bars for endwise reciprocating the same and thereby the rollers connected therewith.

3. The combination of an ink-table, ink-distributing rollers, slideable bearing blocks disposed in superposed order, the upper bearing blocks being supported by the lower bearing blocks, said rollers having journals to rotatively fit the respective bearing blocks, racks connected with the respective bearing blocks, and oppositely-oscillatory pinions in mesh with the respective rack bars for endwise reciprocating the same in sets.

4. The combination of an ink-table, ink-distributing rollers, bearing blocks disposed in sets and having T slots the rollers having T journals to rotatively fit in said T slots, rack bars connected with the respective bearing blocks, and oppositely oscillatory pinions in mesh with sets of the rack bars, for endwise reciprocating the same.

5. The combination of an ink-table, ink-distributing rollers, rack-bars connected with the respective rollers for endwise reciprocating the same, an oscillatory shaft provided with pinions in mesh with certain of the rack-bars, a second oscillatory shaft provided with a pinion in mesh with the remainder of the rack bars and provided also with a second pinion in mesh with one of the pinions on the first mentioned shaft.

6. The combination of an ink table, a plurality of ink distributing rollers, upper and lower rack bars connected with and adapted to longitudinally reciprocate the rollers, a shaft provided with two pinions, one of which meshes with two opposite rack bars, the other pinion being wide-faced and meshing with two other opposite rack bars, and an oscillatory shaft provided with two pinions, one of which is in mesh with the remaining two opposite rack bars and the other of which is in mesh with said wide-faced pinion.

In testimony whereof I affix my signature in presence of two witnesses.

EDWARD J. F. REA.
